UNITED STATES PATENT OFFICE.

HIRAM S. MAXIM, OF PARIS, FRANCE.

REGULATOR FOR DYNAMO-ELECTRIC MACHINES.

SPECIFICATION forming part of Letters Patent No. 269,805, dated December 26, 1882.

Application filed August 31, 1882. (No model.)

To all whom it may concern:

Be it known that I, HIRAM S. MAXIM, a citizen of the United States, at present residing in Paris, in the Republic of France, have invented certain new and useful Improvements in Electro-Magnetic Regulators for Dynamo-Electric Machines, of which the following is a specification, reference being had to the drawings accompanying and forming a part of the same.

In a patent granted to me under date of June 18, 1880, No. 228,543, I have shown and described a device for regulating dynamo-electric machines in respect to the amount of electricity produced, the principle of construction of such devices being substantially as follows: The collecting-brushes are carried by a sleeve capable of rotary movement about the commutator. A toothed sector projects from the sleeve and engages with a bevel-gear on a spindle that is driven in one direction or the other or allowed to remain stationary, according to the position of an armature-lever operated by an electro-magnet in a shunt to the circuit of the regulated machine or a machine whose field is excited by the same, and which operates to shift the position of a double disk, between which revolves a friction-wheel. By this arrangement the brushes are shifted toward or from those points of the commutator from which the maximum amount of current passes to the line, and, as is now well understood, the amount of current is thus regulated to meet the requirements of the line or external circuit, for, assuming, by way of illustration, that the resistance of the main circuit, in the case of a system involving a number of incandescent lamps or similar electrical devices run in multiple arc, is increased by the sudden withdrawal of a number of the lamps, the increased flow of current through the shunt containing the regulating-magnet causes the magnet to attract and shift its armature, and to thereby effect the shifting of the brushes away from the maximum points of the commutator, so that they take off less current. The reverse of this operation, which takes place when lamps are inserted and more current needed, will be readily understood.

Now, it will be observed, in the case of an apparatus of the mechanical construction above

described, that the character of the work performed by the regulating-magnet greatly impairs its sensitiveness, for the weight of the disks, together with the pressure that must be maintained in order that the friction-wheel may act properly, make up a load which necessitates a considerable amount of magnetic strength for its support and comparatively marked variations in current strength to produce the proper movements of the armature.

My present invention involves improvements on the device above described, the said improvements consisting mainly in a construction by means of which the armature of the regulating-magnet is relieved of practically all of its load.

The invention further embraces improvements in the construction and arrangement of the several parts of the apparatus, and in the combination therewith of a safety device, the character of which will be more fully herein-after set forth.

In the accompanying drawings, Figure 1 is a view in perspective of a machine and regulator combined. Fig. 2 is a central vertical section of the same at right angles to the armature-shaft.

The machine or generator is mounted on a base, A, and consists of field-magnets B B, between which revolves an annular armature, C, mounted in standards D D'. Upon the commutator E bear collecting-brushes F F, that are carried by an arm or plate, f, fixed to a sleeve, G, that surrounds the armature-shaft c and extends through the bearings in the standard D. A toothed sector, g, extends downward from the sleeve G.

The regulating mechanism is mounted on a plate, A', secured to the top of the field-magnets B. From plate A' rise four or other proper number of supports, b, sustaining a smaller plate, B'. Upon this plate are secured two electro-magnets, M N, with vertical cores wound with fine wire, and standards H H H, in which are suspended by short arms or ears e and the straps e' armature-levers M' N'.

In a frame, I, secured to base A', are spindles p t, each of which carries a ratchet-wheel, with teeth turned in one direction, and a plain cog-wheel of smaller diameter than the ratchet-wheels.

Mounted in one side of frame I and in a standard, K, is a shaft, L, carrying a cog-wheel, K', at one end, that engages with both the cog-wheels P' T', and a bevel-gear, k, meshing with 5 a similar bevel-gear, k', on a shaft, R, that revolves in bearings in an arm of the standard K and in a bracket, R', secured to the standard D. A bevel-wheel, r', at the lower end of the rod R meshes with the sector g.

10 On the base A, between the poles of the magnet, is mounted a pulley-wheel, C', on the shaft of which is a smaller wheel, F'. In bearings attached to the upper connecting plate of the magnets is a second shaft, G', carrying a large 15 pulley-wheel, C'', and on the armature-shaft is another pulley-wheel, F''. These several wheels are connected by cords or bands, the wheel F'' with the wheel C', the wheel F' with the wheel C'', so that the rotary movement of the 20 armature will be imparted to the shaft G', but so much reduced that the latter will have a comparatively slow motion.

In arms b' b' is mounted a rock-shaft, U, that receives a reciprocating movement from shaft 25 G' by a connecting-rod, g', hinged to the end of a short arm, u, fixed to rock-shaft U, and eccentrically pivoted to a disk, g'', on the end of the shaft G'. An arm, V, is clamped to rock-shaft U, and to the end of this is hinged a lever, 30 arranged to act as a double pawl, in conjunction with the wheels P T and vibrating armature M', with which it is connected by a wire or spiral spring, S.

Of the above-described apparatus the operation is as follows: When an increase of resistance in the external circuit takes place, as by the withdrawal of lamps, a greater amount of current is diverted through the shunt or derived circuit (designated by W W) and the magnet M is in consequence energized to a sufficient degree to draw down its armature and the lever M. This lowers the lever V, so that a tooth on its under side engages with the lower ratchet-wheel, T, and causes the latter to 45 revolve one tooth for every forward movement of the lever V'. This movement being transmitted by the system of gears to the sector g, the brushes are moved away from their former position, and less current taken off. A condition of equilibrium is in this way rapidly attained, when the magnet M, being incapable of longer holding its armature down, allows it to rise until the lever V' takes a position midway between the two ratchets P and T. No 50 change will then occur in the production of current until a further change in external resistances takes place. If more lamps be inserted between the main conductors, the magnet M loses strength, lever M' rises still higher, 55 carrying with it lever V'. The latter, engaging with ratchet P, turns back the brushes until the amount of current generated again causes the magnet M to draw down its armature to a point where the lever V' will engage 60 with neither ratchet.

In order that the ratchets may not be turned

so far as to reverse the brushes in case the armature-lever M' should fail to raise or lower the lever V' at the proper times, a portion of the peripheries of the ratchet-wheels is formed 70 without teeth, as shown in the drawings. When either ratchet has been turned sufficiently to bring the smooth portions under the teeth of the lever V', no further movement of the ratchet in that direction is possible. 75

On the plate B' is shown a safety-magnet, N. This magnet is included in the same circuit with magnet M, and is of practically the same character. Its armature-lever is, however, adjusted by means of a spring or weight 80 in such manner as to be drawn down only by a very strong current.

The field-magnets B B of the machine are wound with a conductor, the ends of which are at the binding-posts x x'. To excite the 85 field, therefore, a conductor, y, is brought from one of the brushes to the binding-post x, and the post x' connected with one of the line-wires. A wire, z, is carried from post x to the metal standards, by which the armature-lever N' is 90 supported, and a wire, z', from the other post, x', is connected to an insulated standard, H', provided with screws n n', that limit the movement of the lever N'. This magnet N and its appurtenances are designed as a safety device 95 for the protection of the machine or lamps in case of such accidents as the sudden extinguishment of a large number of lamps or the rupture of the main conductors at a point where the lamps or other devices remaining in circuit 100 would be liable to injury. It operates to close a shunt-circuit around the field-magnets of the generator on the occurrence of an abnormal flow of current through the magnet-circuit by drawing down the lever N' upon the lower screw, n', thus bringing together the two 105 ends of the circuit z z'. The closing of this circuit stops the generation of current in proportion to the amount of current diverted from the field by the shunt, so that although the 110 stoppage is only momentary the regulator in the meantime has had time to shift the brushes to a position of safety, and the lamps in the 115 circuit are not injured.

The above-described regulator and generator, in the condition in which it has been described, is designed particularly for use in a system in which the field-magnets of one or a number of machines are energized by a separate machine, called the "exciter," in which 120 event the circuit of the magnets M N will be derived from that of the generator or generators, the regulated machine being used as the exciter. From the nature of the case, however, it will be readily seen that whenever it 125 may be necessary to effect an automatic regulation of a machine or machines in respect to the amount of current generated the present invention is of the highest value.

Though shown in combination with a special 130 form of machine, the regulating devices may be equally well applied to many others, and al-

though I consider the arrangement of parts shown as the most convenient and practicable, I do not restrict myself to the same.

Having now described my invention, what I claim as new, and desire to secure by Letters Patent, is—

1. The combination, with a dynamo-electric machine, of brushes arranged to revolve about the commutator, a system of gears for shifting the brushes, a reciprocating lever or pawl arranged to impart movement to the gears in either direction, and an electro-magnet controlling the position of the reciprocating pawl, all substantially as set forth.
- 15 2. The combination, with a dynamo-electric machine, of brushes arranged to revolve about the commutator, a system of gears for shifting the brushes, a rock-shaft oscillated by the armature-shaft, a lever or pawl for imparting movement to the system of gears in either direction, connected with and reciprocated by the rock-shaft, and an electro-magnet for controlling the position of the reciprocating pawl, all substantially as herein set forth.
- 25 3. The combination, with a dynamo-electric machine, of brushes arranged to revolve around the commutator, a system of gears for shifting the same, a rock-shaft and connecting-gear between the same and the armature-shaft, said gear being constructed to reduce and convert the movement of the armature-shaft, as described, a lever or pawl reciprocated by the rock-shaft and arranged for engagement with the brush-shifting gears, and an electro-mag-

net for controlling the degree of elevation of 35 the pawl, whereby the brushes may be turned in either direction, as and for the purpose set forth.

4. The combination, with a dynamo-electric machine, of a bed-plate secured to the field-magnets, a brush-shifting mechanism mounted on said plate, gearing with a revolving brush-holder, a second base or plate supported by standards above the first, electro-magnets mounted thereon, and connections from the 45 same to the brush-shifting mechanism, these parts being constructed and combined in substantially the manner described.

5. The combination, with a dynamo-electric machine and regulator, substantially as herein 50 described, of a normally-open shunt-circuit around the field of said machine, and an electro-magnet in a circuit derived from that of the machine, constructed or arranged to close said shunt-circuit, substantially as set forth.

6. In a regulator for dynamo-electric machines, the combination, with a reciprocating pawl and electro-magnet controlling the same, of ratchet-wheels formed as described, a revolving brush-holder, and a system of gears 60 between the holder and the ratchets, substantially as set forth.

In testimony whereof I have hereunto set my hand this 17th day of June, 1882.
